SAFETY RAZOR BLADE SHARPENER

Robert Alexander Ferdinand Ohlendorf, Buenos Aires, Argentina, assignor, by mesne assignments, to Felipe Saettone, Buenos Aires, Argentina

Application June 25, 1936, Serial No. 87,302
In Argentina July 3, 1935

3 Claims. (Cl. 51—59)

The present invention relates to an apparatus for whetting and sharpening safety razor blades, and the principal object of the invention is the provision of a simple, but practical, blade carrying device for use in whetting and sharpening razor blades. By practicing this invention it is possible to restore blades which are very much worn out to efficient shaving condition.

There have been many devices for this same purpose, but the known devices are generally undesirable, because they are either of complicated construction, which means that they are relatively expensive and easily broken, or that they are of simple construction but so designed that great skill is necessary if the blade is to be properly sharpened.

The present invention avoids the disadvantages of the known whetting and sharpening devices referred to. The apparatus according to the present invention is advantageously distinguished from those now on the market by its extremely simple construction, and low cost. The apparatus has no complicated construction or mechanism to be easily worn out or broken; it is of almost unlimited duration. The operation of the apparatus is of such simplicity that it may be performed by anybody, the apparatus being so constructed that a whetting or sharpening contrary to the cutting edge of the safety razor blade is rendered impossible. The whetting operation is always efficient and never fails, because the inclination and the counter-pressure of the safety razor blade under treatment are so provided for that perfect whetting or sharpening is secured.

The invention consists in a device for use in whetting or sharpening razor blades, comprising two superimposed inflexible frames having a rectangular aperture therethrough for the blade, slidably arranged blade holding means adapted to support the blade in a plane at right angles to the frames, and retaining means provided with a pair of short, relatively narrow notches into which the side edges of the blade extend. Thus whetting or sharpening of the blade can be effected by moving a finger, or suitable whetting element, along the frames transverse to the blade with flexure of the latter during passage of the finger or element thereover.

The apparatus according to the invention, also comprises the feature that the superimposed supporting frames are provided with rods arranged along the longitudinal edges thereof, said rods being sufficiently high to permit the safety razor blade carrier to be placed on a table or flat surface, without said blade touching the surface, said

rods serving also as guide members for a separate whetting or sharpening element.

Additional features of the present invention will become evident from the following specification of the safety razor blade sharpener, with reference to the accompanying drawings, on which:

Figure 1 is a plan view of the lower frame of the blade carrier according to this invention;

Figure 2 is an underneath plan view of the upper frame of the blade carrier according to this invention;

Figure 3 is a plan view of the blade holder, and

Figure 4 is a plan view of the grooved member, carried by the frames shown in Figures 1 and 2;

Figure 5 is a plan view of the blade carrier as illustrated in Figures 1 to 4 in slightly modified form, showing the blade holder and grooved member in dotted lines;

Figure 6 is a perspective view of the blade carrier as shown in Figure 5 with a special whetting element placed thereon;

Figure 7 shows by way of example only, a suitable whetting and sharpening element in plan view and cross section, respectively;

Figure 8 is a perspective view of a whetting and sharpening element in a modified form also shown by way of example only.

In these figures the same reference numerals refer to like or corresponding parts shown in different views.

The razor blade whetter or sharpener, according to the present invention and as shown on the accompanying drawings, comprises a blade carrier as shown in Figures 1 to 6, and a whetting or sharpening element as illustrated in Figures 7 and 8.

The blade carrier device according to the invention consists of two superimposed supporting frames 1 of any suitable material each having one end shaped to form a handle 2. The two frames 1 are secured together by screws, nails, or any other suitable means that also serve to secure a spacing frame 3 between them, the spacing frame being cut out at the central portion to provide a flat space for the purpose of receiving a blade holder 4 and a retaining member 5. The frames 1 each have a rectangular central slot 6 and one or more longitudinal slots 7, the latter for receiving projections 8 provided on the blade holder 4 whereby the blade holder is guided in its movement, which can be effected by a small handle or button constituted by one of said projections 8.

The slidable blade holder 4 comprises a comb like portion 9 having three projections or teeth 10. The same is of sheet material and is slidably arranged within cut out portions of the spacing frame 3 between the two supporting frames 1, in such a manner that its projections or teeth 10 may be moved to project over the central slots 6 of the frames 1 in order to engage the usual perforations of the razor blade to be sharpened and to normally carry the latter in a plane at right angles to said supporting frame, the blade being readily disengaged by withdrawing the teeth 10 of the blade holder 4 from the central slot or aperture 6 of said frames.

The retaining member is of sheet material, and has extensions 11 each with a projecting centre portion 12 and a small notch 13. The retaining member is secured to one of the supporting frames 1 in such a manner that the notches or grooves 1 are situated immediately above the centre of the side edges of the perforation 6. The grooves receive the ends of the razor blade to be whetted or sharpened and serve to retain the blade carried by the comb like portion 9 of the blade holder 4 from sliding on the teeth 10 of said comb like portion.

The width of the grooves 13 is preferably so calculated that a razor blade retained therein may have a limited movement of rotation around its central axis, but offers resistance to further movement so as to become flexed to the correct sharpening angle during sharpening as herein-after explained.

A separate whetting or sharpening element 14, not forming part of the invention, adapted to be used in connection with the razor blade carrier according to this invention and as shown by way of example only in Figures 6 and 7 comprises a simple block of any suitable material of square cross section, preferably in the form of a rhomboidal parallelopiped, having the side surfaces covered or coated with different materials, e. g. leather, 15, willow wood, 16, glass, 17, and slate, 18, or the like.

This element 14 may also be of any other cross section and may be of the form as shown by way of example only in the Figure 8, in which two different materials, e. g. leather 15 and willow wood 16 are arranged endwise one adjacent to the other on a curved surface of the element, the opposite side of the latter being provided with small cylindrical rods of glass 17 and slate 18. In this way the element 14 also provides for four different whetting and sharpening surfaces and conveniently comprises some kind of a handle 19.

When using the first described whetting or sharpening element 14, Figure 7, the blade carrier may conveniently be provided with four bars 20 fixed along the longitudinal edges of the supporting frames 1 as shown in Figures 5 and 6, said bars being sufficiently high to permit the blade carrier device with the safety razor blade inserted therein to be placed on a table or the like, without the latter touching the blade. Said bars thus support the blade carrier device, and the handle 2 may be readily dispensed with. On the other hand and what is more important, the bars 20 serve as guide members for the whetting element 14, Figure 7, to be used in connection with said safety razor blade carrier.

The whetting or sharpening element as shown in Figure 8 is designed to be used in connection with the blade carrier according to the Figures 1 and 2, and it has to be stated that with said blade carrier any person may effect whetting or sharp-

ening by using his own finger instead of the special whetting or sharpening element as illustrated.

The device is used as follows:—

Suppose the safety razor blade carrier is to be used in the condition shown in Figures 1 to 4, the blade holder 4 is withdrawn, by moving the projection or button 8 along the slot 7 until the teeth 10 extend only over less than half of the rectangular central perforation 6 provided in the supporting frames 1. The safety razor to be whetted or sharpened is now inserted in the notches or grooves 13 of the retaining member 5 so that the usual perforations of the razor blade are at the same level as the projections or teeth 10 of the blade holder 4. The latter is then moved so that said teeth extend through the usual perforations of the blade. The blade is thus held in a vertical position ready to be submitted to the action of the whetting element 14, which is simply placed upon the upper supporting frame 1 and slid towards the razor blade, so that when it contacts with the latter it will incline and flex the razor blade, which owing to its resilience will offer resistance, while with continued movement it passes over the cutting edge of the blade, effecting a whetting action thereon on one side of the edge, whereupon the other side is similarly treated by moving the whetting element back to its initial position. It will be understood that the whetting element has to be passed completely over the razor blade, so that the latter by its own resilience may strike back to its vertical position, before the whetting element is returned. In this manner it is impossible to effect a whetting operation contrary to the cutting edge of the razor blade. Further, it will be appreciated that when the whetting element is moved to and fro several times, both surfaces of the cutting edge on one side of the razor blade are uniformly whetted or sharpened, and that by simply changing the contact surface of the whetting element, the whetting or sharpening may be readily effected first with one material such as leather, and thereafter with another material such as glass or the like, in order to secure a proper shaving condition of the cutting edge of the razor blade. In order to whet or sharpen the other cutting edge of the razor blade, it is not necessary to touch the same; the blade carrier device is simply turned over and the opposite surface thereof as a guide for the sharpening element. When using the carrier device as illustrated in Figures 5 and 6 in connection with the whetting and sharpening element 14 of Figure 7, in the way as clearly shown in the Figure 6, it will be noted that the bars 20 properly guide the whetting element in such a way that the latter when moved to and fro over the razor blade, it contacts therewith under a certain angle with respect to the position of the blade and thus is still more effective in the whetting and sharpening of the same. After completing the whetting and sharpening operation, the blade holder 4 is withdrawn, and the blade being in vertical position may be taken out by hand, without it being necessary to touch the cutting edges thereof.

From the preceding description it will be readily understood and perfectly appreciated that the device according to the present invention, is not only advantageous owing to its simple construction, its low cost and its long duration, but that it is also more efficient and easier to handle than most of the known whetting and sharpening devices.

It will be further understood that the present

invention is not restricted to the particular embodiments as described and shown on the accompanying drawings, but that modifications may be introduced therein without departing from the scope of the following claims.

Having thus described my invention, I claim as new and desire to secure by Letters Patent:—

1. A device for use in whetting or sharpening safety razor blades, comprising two superimposed inflexible frames having an aperture therethrough for a blade, blade holding means slidably arranged between said frames and adapted to be moved in and out of said aperture and to freely support the blade within said frames normally in a plane perpendicular to said frames, and blade retaining means also arranged between said frames and provided with a pair of short, relatively narrow notches into which the side edges of the blade extend; and upstanding ribs disposed on the upper surface of said frames to accommodate a separate whetting element therebetween, sharpening of the blade being effected by to and fro sliding movement of the whetting element across the blade with flexure of the latter during passage of the whetter thereover.

2. A device for use in whetting or sharpening safety razor blades, comprising two superimposed, rigidly interconnected inflexible frames with one end thereof shaped as a handle, said frames being spaced apart by an interposed spacing frame, said frames having an aperture therethrough to receive a blade, blade holding means slidably arranged between said frames and adapted to be moved in and out of said aperture and to freely support the blade within said frames normally perpendicular to said frames, said blade holding means consisting of sheet material and

comprising a comb like portion adapted to engage the perforations of the blade to be sharpened and a body portion provided with projections extending into longitudinal slots in the first-mentioned frames for moving and guiding the blade holder for engaging or disengaging the blade, and blade retaining means also arranged between said frames and provided with a pair of short, relatively narrow notches into which the side edges of the blade extend, whereby sharpening of the blade can be effected by sliding movement of a person's finger or separate whetting element along the frames across the blade with flexure of the latter during passage of the whetter thereover.

3. A device for use on whetting or sharpening safety razor blades, having a slideable blade holder of sheet material, said blade holder comprising a comb like portion and a rearwardly extending body portion with one or more vertically extending projections, a blade retaining member of similar sheet material having lateral extensions each provided with a short relatively narrow notch, two superimposed frames for supporting said blade holder and said retaining member, a spacing frame between said superimposed supporting frames providing between the latter the required space for receiving and housing said blade holder and said retaining member; a central rectangular aperture in said supporting frames into which extend said comb like portion of the blade holder and said retaining member, and within which the blade to be sharpened is held and retained during the whetting or sharpening operation.
